(57) **CLAIM**

The ornamental designs for an elongate vehicle light assembly, as shown and described.

DESCRIPTION

FIG. 1 is a perspective view of an elongate vehicle light assembly embodying my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a front view of an alternative design, the remaining views thereof being the same as FIGS. 2-7.

The broken line showing of the bracket is for illustrative purposes only and forms no part of the claimed design.
